[57] CLAIM

The ornamental design for a message holder, as shown.

DESCRIPTION

FIG. 1 is a plan view showing the front of the message holder;

FIG. 2 is an elevation view of the top of the message holder, looking down upon FIG. 1 from the plane of line 2—2;

FIG. 3 is an elevation view of the bottom of the message holder, looking up upon FIG. 1, from the plane of line 3—3;

FIG. 4 is an elevation view of the left side of the message holder, looking upon FIG. 1, from the plane of line 4—4;

FIG. 5 is an elevation view of the right side of the message holder looking at FIG. 1 from the plane of line 5—5; and

FIG. 6 is a plan view of the rear of the message holder.
